RAY C. FLAGG, OF EASTWOOD, NEW YORK, ASSIGNOR TO FLAGG-STOWELL COMPANY, OF SYRACUSE, NEW YORK, A COPARTNERSHIP COMPOSED OF RAY C. FLAGG AND ORLA E. STOWELL.

BRAKE-LOCKING DEVICE.

1,412,397.

Specification of Letters Patent. Patented Apr. 11, 1922.

Application filed June 29, 1921. Serial No. 481,364.

To all whom it may concern:

Be it known that I, RAY C. FLAGG, of Eastwood, in the county of Onondaga, in the State of New York, have invented new and 5 useful Improvements in Brake-Locking Devices, of which the following, taken in connection with the accompanying drawings, is a full, clear, and exact description.

This invention relates to a locking device 10 for the service brake of Ford cars and other machines employing a pedal-operated-brake and an emergency-brake-operating-lever, the object being to provide simple and efficient means whereby when the pedal-brake-lever 15 is forced to its braking position the operation of the emergency-brake-lever will automatically lock the pedal-lever in its operative position.

Other objects and uses relating to specific 20 parts of the brake-locking-device will be brought out in the following description:

In the drawings:

Fig. 1 is a side elevation of a portion of an 25 internal combustion engine together with the service-brake-pedal and emergency-brake-lever and my improved locking device operatively connected to those parts which are shown by full lines in their normal position and by dotted lines in their operative 30 position for setting the brake.

Fig. 2 is an enlarged detail sectional view 35 of a portion of the locking mechanism in its locking position.

In order that my invention may be clearly 40 understood, I have shown a portion of an internal combustion engine —A—, a service-brake-lever —1— and an emergency-brake-lever —2— as commonly used in Ford cars, the emergency-brake-lever —2— being pivoted at —3— to move along a toothed segment —4— and is provided with a pivoted pawl —5— adapted to engage the teeth of said segment to hold the lever in its various positions of adjustment, said 45 pawl being releasable by means of a hand-operated-rod —6— and pivoted hand-piece —7— as shown in Fig. 1.

The service-brake —1— is pivoted as usual at —8— to a portion of the engine 50 frame or rather to the clutch-case for controlling the brake in the usual manner, the brake-lever —2— being connected by a rod —9— to the usual devices for operating the brake-band against the drum of the rear axle.

The brake-locking-attachment comprises a bar —10— suitably secured by bolts or screws —11— and —12— to portions of the engine frame for receiving and supporting a locking-pawl —13— which, in this instance, is pivoted at —14— intermediate its ends and has its lower end provided with an aperture —15— for receiving one end of a rod —16—, the upper end of said pawl —13— being also provided with a transverse opening —17— forming lower and upper biting nibs —18— and —19— for engaging opposite sides of a rod —21— which is pivotally connected at one end at —22— to a clamp —23— on the upper end of the pedal-lever —1— just below its pedal —24—.

The rear end of the rod —16— is pivotally connected at —25— to an extension —26— on the lower end of the lever —2—, while the front end of the same rod is passed 75 through the aperture —15— in the lower end of the pawl —13— and is provided with shoulders —26— and —27— engaging opposite faces of said pawl, one of said shoulders as —27— being movable lengthwise of the 80 rod —16— and forms an abutment for one end of the coil spring —28—. This coil spring surrounds the adjacent portion of the rod —16— and has its other end abutting against a fixed shoulder —30— on said rod, 85 thereby establishing a yielding connection between the rod —16— and lower end of the pawl —13—.

The upper end of the pawl —13— normally rests against a stop —29— on the bar 90 —10—.

Operation: Assuming now that the hand-lever —2— is in its normal position for releasing the rear brake and that it is desired to apply the service brake by the operation 95 of the lever —1— from its normal position, shown by full lines in Figure 1, under which conditions the pawl —13— would be in the position shown by full lines in the same figure, whereupon the forward movement of the pedal-lever —1— will cause a similar forward movement of the rod —21— through the opening —17— in the upper end of the pawl —13— and then by rocking the hand-lever —2— rearwardly to the position shown by dotted lines for applying the rear brake will throw the rod —16— forwardly and through the medium of the spring —28— will rock the lower end of the lever —13— forwardly and its upper end 110

rearwardly along the rod —21— until its nibs —18— and —19— engage opposite sides of the rod —21— so that when the hand-lever —2— is locked in its adjusted 5 position by means of the pawl —5— and rack —4—, the nibs —18— and —19— will obtain a biting grip upon the forward end of the rod —21— to hold the pedal or service-brake-lever —1— in its braking position.

It is, of course, understood that the brake-lever —2— is positively held in its adjusted position by the engagement of the pawl —5— with the teeth of the rack —4— and 15 that even though this brake-lever may be thrown to its braking position before the 20 operation of the service-brake-lever —1—, the latter may nevertheless be moved forwardly, thereby forcing the rod —21— forwardly through the opening —17— even 25 though the nibs —19— and —20— may be in engagement with the upper and lower sides of said rod because in that case, the upper end of the pawl —13— will be free to rock forwardly against the action of the spring —28— which latter, however, holds the pawl in position to engage its nibs —18— and —19— with the rod —21— so 30 that any tendency of the lever —1— and its rod —21— to return rearwardly is prevented by the engagement of the nibs —18— and —19— therewith.

The locking mechanism thus far described, is particularly effective in holding 35 the brake-levers in their braking positions especially when it is necessary to apply both brakes, as for example on side hills, where either brake would be insufficient in itself to properly hold the machine.

40 It is evident, however, that various changes may be made in the detail construction of the various connections between the hand-lever —2— and pedal-lever —1— for

accomplishing the same result without departing from the spirit of this invention, 45 and therefore, I do not wish to limit myself to the precise construction shown and described.

What I claim is:

1. In combination with a service-brake- 50 operating-lever for motor vehicles, a pivoted pawl having an opening therethrough, and biting nibs at opposite sides of the opening, a rod pivotally connected to the lever extending through said opening in the pawl to 55 be engaged by said nibs for holding the lever in its braking position, and means for operating the pawl to cause its nibs to engage said rod.

2. In combination with a service-brake- 60 operating-lever for motor vehicles, a pivoted pawl having opposed biting nibs in spaced relation, a rod connected to and operated by said lever between said nibs, an emergency- 65 brake-operating-lever, and means actuated thereby for rocking said pawl to cause its nibs to engage opposite faces of said rod for holding the service-brake-operating-lever in its braking position.

3. In combination with a service-brake- 70 operating-lever, a pivoted pawl having opposed biting nibs in spaced relation, a rod actuated by said lever between said nibs, an emergency-brake-operating-lever, and yielding connections between the last named 75 lever and said pawl for rocking the latter about its pivot and causing said nibs to engage opposite faces of the rod to hold the service-brake-operating-lever in its braking position.

In witness whereof I have hereunto set my hand this 20th day of June, 1921.

RAY C. FLAGG.
